TROLLEY CLAMP

Harry Cappellanti, Morgantown, W. Va., assignor
of one-third to Frank Ellis Christopher, one-
sixth to Philip S. Davis, and one-sixth to
Charles McClellan Davis, all of Morgantown,
W. Va.

Application August 2, 1941, Serial No. 405,237

4 Claims. (Cl. 173—273)

My invention relates to electric circuits employed in mines, and has among its objects and advantages the provision of an improved safety trolley clamp particularly adapted for use in connection with bare tapping systems.

An object of my invention is to provide a trolley clamp designed to provide a positive clamping action and wherein the construction is such as to facilitate quick and easy operation thereof. When in use, the clamp is characterized by a firm grip upon the trolley cable and thereby eliminates the tendency to swing, which is characteristic of conventional hook devices employed in mines. The clamp is also provided with an elastic enclosure to isolate electric sparks within the apparatus itself. Two clamping jaws are employed, which jaws are actuated through the medium of a handle which, when pivoted in one direction, imparts clamping motion to the jaws and, when pivoted in the opposite direction, causes the jaws to release from the trolley cable, thereby preventing the locomotive or machine operators from becoming tangled in the cable connected with the jaws in the event of a runaway or miss while in motion.

In the accompanying drawings:

Figure 1 is a sectional view of a trolley clamp embodying my invention;

Figure 2 is a sectional view taken substantially along the line 2—2 of Figure 1;

Figure 3 is an end view of the clamp jaws in their released positions;

Figure 4 is a view of the opposite end of the clamp jaws also in their releasing positions;

Figure 5 is a side view of the jaws clamping the trolley, with one of the jaws partly broken away for the purpose of illustration;

Figure 6 is a view taken along the line 6—6 of Figure 5;

Figure 7 is a view taken along the line 7—7 of Figure 5;

Figure 8 is a sectional view of a modified form of the handle construction;

Figure 9 is an inner face view of one of the jaws;

Figure 10 is an inner face view of the other jaw;

Figure 11 is an end view of a cam coating with the jaws of Figures 9 and 10 for clamping the jaws upon the trolley;

Figure 12 is an opposite end view of the cam;

Figure 13 is an end view of a cable securing means;

Figure 14 is a view of the opposite end of the part of Figure 13;

Figure 15 is a detail view of a spring biasing the jaws of Figures 9 and 10 to an open position;

Figure 16 is a detail view of a spring employed for latching the jaw actuating handle in its jaw clamping position;

Figure 17 is a sectional view of a modified trolley clamp wherein a fuse is incorporated in the handle of the clamp;

Figures 18, 19 and 20 are detail views of the fuse mounting means; and

Figure 21 is a perspective view of a rubber boot enclosing the greater portion of the clamping jaws to isolate electric sparks within the clamped cell.

15 In the embodiment selected for illustration, the trolley clamp comprises two jaws 10 and 12 recessed at 14 to substantially embrace the trolley cable 16 when the jaws are clamped thereon, as shown in Figure 6. Figure 2 illustrates the 20 jaws in their trolley releasing positions, which is also true of Figures 3 and 4. In Figures 9 and 10, the jaw 10 is provided with two ears 18, each fitting loosely between two spaced ears 20 formed on the jaw 12. All the ears 18 and 20 are provided with coaxial openings 22 for the reception of a pin 24 about which the two jaws 10 and 25 12 pivot.

Means for yieldingly biasing the jaws 10 and 12 to their open positions comprises a spring 26 30 having the legs 28 thereof lying in grooves 30 in the jaws so as to be restrained from accidental displacement. Upon the pin 24, see Figures 1 and 2, is mounted a swivel member 32 having a bore 34 loosely receiving the pin. The ear portion 36 of the swivel member is loosely receivable 35 between spaced ears 38 at one end of a clamp stem 40, the ears 36 and 38 being bored to receive a pin 42. Swivel member 32 is loose on the pin 24 and the ears 38 of the stem 40 may 40 also pivot on the pin 42, the latter being located at right angles to the pin 24.

Each jaw 10 and 12 is provided with a finger 44 and the stem 40 is provided with a wedge-shaped formation 46 arranged to enter between 45 the two fingers 44 for separating the fingers and pivoting the jaws 10 and 12 into clamped engagement with the trolley 16 when the stem 40 is pivoted to the position of Figure 5. Each jaw 10 and 12 also includes a short finger 48 arranged to be engaged by a shoulder or stop 50 on the stem 40 when the latter is pivoted to its jaw releasing position of Figures 1 and 2. When in the latter position, the wedge-shaped formation 46 projects a short distance between the 55 fingers 44 but provides sufficient clearance to per-

mit the spring 26 to pivot the jaws to their open positions, with the short fingers 48 engaging one with the other to restrain the jaws from further pivotal movement.

Upon the stem 40 is formed a cylindrical body 52 threadedly connected in a metallic sleeve 54 secured in one end of a tubular handle 56 formed of insulated material. The legs 58 of the generally U-shaped spring extend loosely through openings 60 in an end wall 62 of the body 52 and are bent to provide right angular pins 64 and loosely receivable in a transverse bore 66 in the stem 40. The bight 68 connecting the legs 58 is of curved formation to extend partly about the stem 40 underneath the wall 62, the body 52 being provided with an axial bore 70 for accommodating the bight.

Figures 9 and 10 illustrate the fingers 44 as each having a groove 72 into which the legs 58 snap when the handle 56 is pivoted to the position of Figure 5. Each of the fingers 44 is also recessed at 74 to partially embrace the stem 40 underneath the wedge-shaped formation 46 when the handle is in the position of Figure 5. Thus the handle is firmly latched in the clamped position of the jaws 10 and 12.

In Figure 1, the stem 40 is provided with a threaded shank 76 threaded into a cable clamp part 78 having a threaded body 80 threadedly receivable in a threaded bore 82 in a companion cable clamp part 84. A cable 86 extends inside the tubular handle 56 and the insulation of the cable is cut away with the bared wires 88 extending through a bore 90 in the part 84. This part is provided with a circumferential shoulder 92 having an annular groove 94. On the end of the body 80 is formed an annular bead 96 opposing the annular groove 94. A conical-shaped wire spreading point 98 is formed at the end of the body 80 coaxially with the opening 90. Thus the point 98 spreads the wire ends laterally so that the wire ends may be clamped between the shoulder 92 and the bead 96, as at 100. Both parts 78 and 84 are flattened at 102 to facilitate the application of wrenches thereto so that the two parts may be firmly connected for tightly pressing the wire ends between the ledge and the bead. The lower end of the handle 56 is provided with an opening 104 which snugly receives the cable 86, the latter being of such length as to connect with the machine located to one side of the trolley 16. The handle 16 pivots in a plane longitudinally intersecting the trolley 16 and mere pivotal movement of the handle to the position of Figure 1 releases the jaws 10 and 12 so that the latter may be removed or dropped from the trolley.

A rubber boot 106 is slipped over the stem 40 above the handle 56 and embraces the jaw portions underneath the trolley 16 so as to confine electric sparks within the jaw assembly.

Figure 8 illustrates a modification in which the stem 108, corresponding to the stem 40, is provided with a threaded shank 110 secured in a threaded bore 112 in the cable clamp part 114 corresponding to the part 78. In this form, a sleeve 116 of insulating material is provided with a threaded metallic sleeve 118 threaded into a metallic sleeve 120 secured in the end of the insulated handle 122 corresponding to the handle 26.

In Figure 17, the stem 124 is threaded into a body 126 provided with an annular wall 128 into which the cap end 130 of a fuse 132 is pressed.

Slots 134 are formed in the wall 128 so that the divided wall includes an element of resiliency to provide a firm frictional connection for the cap end 30. The opposite cap end 136 of the fuse 132 is pressed into an annular wall 138 in a clamp part 140 corresponding to the clamp part 78. Wall 138 is also slotted at 142 in the same manner as the wall 128.

Figure 17 also embodies a further modification in that the stem 124 has two wedge-shaped formations 144, each coacting with a set of fingers 146 on the jaws, which are in other respects similar to the jaws 10 and 12. Thus the jaws may be pivoted to trolley clamping positions through pivotal movement of the stem 124 in either direction.

The jaw 10 is provided with a curved lip 148 which serves as a guide contact with the trolley 16 should it be desired to move the clamp along the trolley 16 and still supply current to the machine operated by the cable 86.

Without further elaboration, the foregoing will so fully illustrate my invention, that others may, by applying current knowledge, readily adapt the same for use under various conditions of service.

I claim:

1. A trolley clamp comprising two jaws each provided with a downwardly extending finger, the fingers being arranged in opposed relation, a pivot connecting the jaws, a spring located between the jaws tending constantly to move them into opened relation, a swivel member mounted on the pivot at one side of the fingers for lateral movement with relation to the fingers, a cable handle provided at its upper end with a wedge shaped member located between the fingers, and a pivot connecting the upper end of the cable handle to the swivel member for movement with relation to the fingers at right angles to the direction of movement of the swivel member so as to move the wedge shaped member upwardly or downwardly with relation to the fingers and thus close the jaws or release them for movement into opened position by the spring.

2. A trolley clamp as set forth in claim 1, wherein each finger is provided in its inner face with a groove, and wherein the cable handle is provided with spring elements adapted to engage in the grooves when the handle is in jaw closing position, whereby to latch the handle in such position.

3. A trolley clamp as set forth in claim 1, wherein each jaw is provided with a second finger, these fingers extending downwardly from the jaws in opposed relation and being located at that side of the swivel member remote from said first fingers, the fingers being adapted to contact with each other to limit the opening movement of the jaws.

4. A trolley clamp as set forth in claim 1, wherein each jaw is provided with a second finger, these fingers extending downwardly from the jaws and being located at that side of the swivel member remote from said first fingers, the fingers being arranged in opposed relation and adapted to contact with each other to limit the opening movement of the jaws, and wherein the cable handle is provided with a shoulder adapted to contact with the lower ends of said second fingers when the handle is in jaw releasing position, said shoulder and second fingers constituting means adapted to prevent the withdrawal of the wedge shaped member from between said first fingers.

HARRY CAPPELLANTI.
